2,250,604

ROLLING DOOR WITH RELEASABLE GUIDE GROOVE

Joel S. Poorman and Ralph H. Gregor, Columbus, Ohio, assignors to The Kinnear Manufacturing Company, Columbus, Ohio, a corporation of Ohio

Application October 20, 1939, Serial No. 300,424

3 Claims. (Cl. 189—56)

This invention relates to an improvement in door construction, and more particularly to rolling doors such as used for closing openings on trucks, trailer bodies, railway box cars, and the like conveyances.

It is a principal object of this invention to provide a slidable door with a releasable hinged guide member whereby the door can be readily freed from its guides, when it has become jammed.

It is another object to provide an improved door construction wherein releasable guide members are installed at both sides of the door which, in case of emergency, can be moved away from the door edges to permit outward movement of the door.

Another object is to provide a flexible door curtain having a releasable hinged groove member forming the outside curtain guide portions which can be swung away from the curtain whereby the curtain can be pulled forward to free it from its side guides in case the curtain has become wedged thereagainst.

Another object is to provide a slidable door member with outer releasable guide means which ordinarily are locked in fixed position and in the case of emergency can be unlocked and swung away from engagement with the door.

These and other objects and advantages will be apparent as the description proceeds.

In the accompanying drawings forming a part of this specification:

Figure 1 is an end elevation view of a truck trailer having a rear door equipped with releasable hinged guide members according to this invention;

Figure 2 is a sectional view taken substantially on the line 2—2 of Figure 1, with certain parts broken away to show the construction more clearly;

Figure 3 is a fragmentary detail sectional view showing the hinged groove guide swung to an open position;

Figure 4 is a fragmentary detail sectional view taken on the line 4—4 of Figure 1, and looking in the direction of the arrows;

Figure 5 is a similar fragmentary sectional view taken on the line 5—5 of Figure 1;

Figure 6 is a vertical end sectional view of the door, partly broken away, and taken on the line 6—6 of Figure 1 looking in the direction of the arrows;

Figure 7 is a similar sectional view as in Figure 6, showing the outer door guide groove member swung outward in open position;

Figure 8 is an end elevation view of the door, partly broken away, illustrating the releasable groove guide swung outward away from the edges of the door.

Referring to the drawings in detail, there is illustrated in Figure 1 a truck trailer, generally designated 10, mounted for transportation on the chassis 11. The trailer is provided with a vertically slidable or rolling door 12 which is made up of articulated slats 13. The door is mounted to reciprocate in the groove formed along the edges of the door, the lower outer portion of which is closed by means of the releasable guide members 14. As shown in Figure 1, the groove-forming outer guide members 14 are used at both sides of the door opening and extend from the floor level of the trailer body to within $\frac{2}{3}$ to $\frac{3}{4}$ of the height of the door opening. Above this point the side guide members are fixed.

As shown in Figures 2, 3, 4, and 5, the truck body 10 comprises a frame 15 having the siding 16 and inner lining or bracing 17. Suitably fixed to the frame upright member 15 and lining 17, adjacent the sides of the doorway, is an angle member 19 which forms the inside guide member for the groove 21 along which the rollers or sliding end portions 22 of the door move during opening and closing of the door. The angle members 19 are permanently positioned in place by means of screws or bolts as at 23.

Above the releasable outer guide members 14 are provided the fixed strip guide members 25 which form the upper part of the groove guideway 21. These members are fixed to the frame 15 by means of the screws 26 or equivalent fastening means, as shown in Figure 5. The guide members 14 and 25 extend into the doorway and form the outer wall for the groove 21. The outer guide members 14 and 25 may be made of any suitable material such as metal, wood or the like. Preferably when wood is used it is reinforced with outer metal plate such as shown at 27 in order to provide a guide strip which is able to withstand the outward thrust of the door. The outer guide members 14 are equipped with hinges 30 and are adapted to be swung about the pivot pin 31 outward away from the edge of the door 12 and end members 22 so as to permit the door to be pulled outward sufficiently to free it from contact with load or stock which has shifted thereagainst causing binding of the door against the outer guide end member. Any suitable number of hinges may be used for fastening the guide strips 14 onto the frame.

40

45

50

55

For releasably locking the hinged guide members 14 in the position shown in Figure 4, which is the normal operating arrangement, the lever 33 is provided which is pivotally secured to the lower end of the member 25 as at 34. A pair of these levers is employed, one for each hinged guide member, as shown in Figure 1. The lever 33 comprises a handle 35 and an intermediate wedge-shaped latch protuberance 36a which is adapted to engage over the hinged portion 37 and abut the stop member 38 on the hinged portion 37, as shown in Figure 4. Lever 33 also comprises an attaching ear member 36 which is adapted to be brought alongside of the member 38 when locking the hinged guide members in place, as shown in Figs. 1 and 6. Members 36 and 38 are provided with cooperating openings 40 and 41, respectively, which are adapted to receive a lock or sealing means 42 to prevent unauthorized releasing of the guide members 14. The lower end of the door 12 is provided with an angle member 44 and a locking slide bolt 45.

At the upper end of the inner guide angle member 19 there is provided a curved lip guide means 47 which is arranged to guide the flexible door 12 into the groove 21. The flexible curtain forming the door 12 is attached at the upper end to the barrel 48 which is preferably counterbalanced by the spring 49 so as to provide an easily sliding door member.

In operation it will be understood that the releasable outside guide groove members 14 are used only in case of emergency, and under normal operating conditions they will be locked in the closed position to guide the curtain or door 12. The door preferably is of the spring counterbalanced push-up type operated by means of handles on the bottom angle of the curtain, as shown in Figures 6 and 7. The door construction is conventional and forms no part of this invention. Obviously various types of doors may be employed of the rolling or sliding groove kind.

Further, it will be appreciated that this invention is adapted for use on doors of buildings, compartments or the like, other than movable vehicles, to provide an improved door guide construction whereby the door may be readily freed from its guide members in use.

It will be further understood that this invention is not to be limited to the particular details of construction shown but may be varied to suit different conditions and uses.

Having thus fully described our invention, what

we claim as new and desire to secure by Letters Patent is:

1. An improved door guide construction for a rolling door comprising fixed flange members arranged to engage the rear side portion of said door, juxtaposed outer door guide members spaced from said flange members and forming a groove along which the side edge portion of said door is adapted to be guided, the upper portions of said outer door guide members being fixedly secured with respect to said flange and the lower portions being pivotally mounted to swing outward away from the edges of said door to free the lower portion thereof from said groove, and permit the same to swing outwardly from said grooves, while permitting the upper portion of the door to remain in said grooves.

2. An improved door guide construction for a rolling door comprising inner and outer door guide members, said inner door guide members being fixed and the lower portion of said outer door guide members being releasable from the edges of said door to free the same so as to swing outward whereby the lower portion of the door can be moved laterally outward from said door guideway, and means comprising a lever pivotally mounted adjacent the division line between the upper and lower portions of said outer guides having locking means associated therewith for normally maintaining said releasable guide portion in position to guide said door.

3. In combination with a flexible rolling door, of a guide therefor comprising fixed flange members extending inwardly from opposite outer sides of the door opening towards the center thereof and adapted to engage the rear face of the edge portions of said door, outer door guide members spaced from said flange members in parallel relation thereto and forming therewith grooves within which the side edge portions of the door are guided, the upper portion of said outer guide members being fixedly secured with respect to their respective cooperating flange members and the lower portion thereof being pivotally mounted to swing outwardly away from said flanges to free the lower portion of the door and permit the same to swing outwardly away from said grooves while the upper portion of the door is retained in position in said grooves for guiding the door.
